APPARATUS FOR DRYING HAIR

Clarke L. Matthews, St. Louis, Mo., and John L. Turner, East St. Louis, Ill., assignors, by direct and mesne assignments, to Matthews Specialty Corporation, St. Louis, Mo., a corporation of Missouri

Application May 18, 1947, Serial No. 747,296

8 Claims. (Cl. 34—53)

1

This invention relates to apparatus for drying hair and, more particularly, to such apparatus for use in beauty shops.

Among the several objects of the invention may be noted the provision of an improved hair drying apparatus, particularly for beauty shops, adapted to dry the hair in less time than heretofore possible; the provision of a hair drying apparatus of the class described which, in addition to drying the hair in less time, affords comfort to the user by reducing ambient temperatures; and the provision of a hair drying apparatus of this class which is economical, safe and sanitary. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a side elevation, partly in section, of the hair drying apparatus of this invention;

Fig. 2 is an enlarged detail section taken on line 2—2 of Fig. 1;

Fig. 3 is a wiring diagram; and,

Fig. 4 is an enlarged portion of the wiring diagram in an alternative setting.

Similar reference characters indicate corresponding parts throughout the several views of the drawings.

Prior conventional beauty shop hair driers each comprise a drying hood mounted upon a floor stand and including in the hood a fan and heater for blowing a current of heated air upon the customer's head. A primary objection to such driers is the high air temperatures involved and the considerable period of time required properly to dry the hair. This period generally is from forty-five to ninety minutes or more, depending upon the quantity and thickness of the customer's hair and the relative humidity of the air in the drying hood. This air, even at high temperatures, has a relative humidity which is so little below that of the room in which the drier is placed that long drying periods result. For the customer to remain seated with her head in a drying hood and with a current of heated air blowing on her head for such a considerable period of time is a matter of acute discomfort, particularly in warm weather. The considerable drying period also reduces the number of cus-

2

tomers which the beauty shop may accommodate in a given time and represents a loss of income.

Another disadvantage of prior hair driers, from the standpoint of customer comfort, is the noise of the fan in the drying hood, closely adjacent the customer's head. Such driers are also unsanitary, inasmuch as they generally recirculate unfiltered air over and over again, with the addition after each use of the moisture from the previous customer's hair. This, of course, also reduces the effectiveness of the current of heated air for drying purposes.

The present invention provides an improved hair drying apparatus wherein instead of relying for drying upon normally moist air heated to high temperature, with its attendant discomfort, provision is made for causing a flow of very dry air at a lower and comfortable effective temperature upon the hair. With this invention, the period required for drying hair is very considerably reduced and there is no discomfort to the customer during this short period. The invention eliminates the fan in the drying hood and thereby eliminates discomfort due to noise. It provides the sanitary and economic feature of using filtered dry air for every hair drying operation instead of using the same moist air over and over again. It is of such construction as to be incapable of harming the customer.

Referring now particularly to Fig. 1 of the drawing, the apparatus of the invention is shown generally to comprise a portable hair drier 1 having an air distributor 3 carried by a base 5. The latter is hollow and encloses parts of the apparatus to be described. It includes a pedestal 7 supported on casters 9, whereby the hair drier may be wheeled from place to place. The pedestal carries a vertical double-walled casing 11 having an inner cylindric wall 13 and an outer cylindric wall 15 forming an annular cylindric chamber or receptacle 17 surrounding a compartment 19. The lower end of the chamber and compartment are closed by bottom walls 21 and 23, respectively. The annular chamber 17 is open at its top. The inner wall 13 is provided with filter-screened apertures 25 adjacent the lower end of chamber 17 forming ports or outlets for flow of air from the chamber into the compartment 19.

The air distributor 3 is fixed upon the upper end of a hollow standard 27 being in fluid communication therewith. The hollow standard slides through a central aperture in the top of a dome 29 and also through a central aperture in the base 31 of said dome. The base 31 forms a closure for the upper end of the compartment 19.

The dome is fixed to the upstanding peripheral rim 33 of an upper ring 35, the inner margin of the ring being secured to the closure 31. The lower margin of the dome is removably telescoped over the upper end of the outer casing wall 15. The air distributor 3, the hollow standard 27, the dome 29 and the closure 31 are thus removable as a unit from the casing 11.

Below the rim 33, the dome 29 is formed with air intake louvers 37 through which air may flow only into the annular chamber 17. A motor-blower assembly 39, comprising a motor 40 and a blower 41, is carried by the hollow standard 27 within the compartment 19. The blower outlet 42 is in communication with the standard and the blower inlet 43 is in the compartment 19. As illustrated, the motor-blower assembly 39 is suspended from the lower end of the standard 27, the blower outlet 42 being connected to the lower end of a short length of flexible hose 45. The upper end of this hose is connected to the lower end of the standard. The arrangement is such that upon operation of the blower, air is drawn through louvers 37, chamber 17 and ports 25 into compartment 19, thence into the blower inlet 43, and is delivered through blower outlet 42, hose 45 and standard 27 to the air distributor 3. Leakage of air from the compartment 19 is prevented by packing rings 47 and 49 mounted adjacent the apertures in closure 31 and dome 29. These are in slidable sealing engagement with the standard.

The standard 27 has a number of guide arms 51 fixed thereon adjacent its lower end within compartment 19. These arms extend outward from the standard and slide in the channels of channel-iron guides 53. The latter depend vertically within the compartment from closure 31, so as to guide the standard for vertical movement. The assembly comprising the air distributor 3, sliding standard 27, and the motor-blower assembly 39 is suspended by the cables 55 of spring counterbalances 57. The latter are secured to the bottom of closure 31, being located within compartment 19. The lower end of each cable is connected to a guide arm 51, as indicated at 59. The arrangement is such that the air distributor 3 may be adjusted vertically to any desired position by sliding standard 27 up or down within its range of movement. The motor-blower assembly 39 moves with the standard in the course of such adjustment. The weight of the air distributor 3, standard 27, motor-blower assembly 39 and arms 51 is counterbalanced in any adjusted position by the springs of counterbalances 57. The flexible hose suspension and connector 45 isolates from the remainder of the apparatus vibrations of the motor-blower assembly.

The chamber 17 forms a dehydration chamber for dehydrating air as it flows therethrough and contains suitable dehydrating means for this purpose. As illustrated herein, the chamber 17 is partially filled with a solid-particle desiccant 61 which will adsorb and hold moisture without substantial change in form or properties including resistance to airflow; that is, it will not liquefy or obstruct the flow of air therethrough. Between its solid particles are ample permanent voids. It is also desirable that the desiccant be one which is adapted to be reactivated without impairing its dehydrating efficiency so that it may be reused. A particularly suitable desiccant is activated alumina, essentially a porous form of aluminum oxide (Al_2O_3), which is capable of absorbing substantially all the moisture from the 75 thereof.

air without liquefying or becoming non-porous. It is in small-lump form. This desiccant may be reactivated simply by heating to drive off the adsorbed moisture. It may be reactivated an almost unlimited number of times without materially impairing its dehydrating efficiency. Other suitable desiccants having the desired properties, such as silica gel, may also be used.

Electrical resistance heating elements 63, in the form of strip heaters, are mounted on wall 13 within chamber 17. These heaters are adapted to be energized in a manner to be described to heat the desiccant 61 to reactivate it. An annular air filter 65 is also provided in chamber 17 for filtering the air prior to its passage through the desiccant. This filter is inserted into the chamber after it has been loaded with the desiccant and is supported upon lugs 67.

The air distributor 3 includes a manifold 69 connected at its lower end 71 to and in communication with the upper end of standard 27. The manifold curves upward and outward away from the standard and carries a drying hood 75 at its upper end. Hood 75 is lined with a plurality of removable, flexible, air distributing tubes 77 which are in communication at their upper ends with the manifold through nipples 79. The lower ends of the tubes 77 are closed. Each tube has a plurality of apertures 81 therein through which streams of air may flow upon the hair.

Communication from the manifold to the drying hood may also be established through a gate valve 83. This valve comprises a gate 85 which seats upon the wall 87 of the manifold and is slidably between a position wherein it closes a relatively large outlet port 89 in the wall and a position wherein the port is open. Port 89 opens into the top of the drying hood. The gate 85 is guided for sliding movement between open and closed positions by means of a stud 91 which extends through a guide slot 93 in the gate with its end fixed in wall 87. A valve stem 95, for operating the gate, is connected thereto at 97 and extends slidably through a packing 99 to the outside of the manifold. The stem 95 has a knob 101 on its outer end by means of which it may either be pushed in to close valve 83 (Fig. 2) or pulled out to open the valve.

A two-stage electrical resistance heater 103 comprising a pair of heating coils 105 and 107 (Figs. 3 and 4) is mounted in the manifold 69 adjacent its outlet end. This heater is for the purpose of warming the dehydrated air flowing through the manifold to a comfortable effective temperature prior to its emission through apertures 81 in tubes 77 (and through port 89 if open). A manually operable selector switch 109 for controlling the heater 103 is mounted on the drying hood in a readily accessible location. 60 This switch may be set selectively to energize one heating coil for low heat, both heating coils for high heat, or to deenergize both coils completely, as will be made clear. The heater 103 is also under control of a thermostatic circuit breaker 65 111 for deenergizing the heater 103 upon excessive heating. Mounted in the dome 29 is a time-control switch or interval timer 113 for controlling the period of operation of desiccant heaters 63 and certain periods of operation of the motor 40. A main control switch 115 is mounted on the manifold 69. An extension cord 117 having a plug 119 for plugging into an electrical outlet extends into the base 5 of the hair drier for supplying current to the various electrical elements 70 thereof.

As illustrated in Fig. 3, the extension cord 117 comprises wires 121 and 123 connected across a two-phase power line P when plug 119 is inserted into an electrical outlet. These wires lead to terminals 125 and 127. The motor 40 of the motor-blower assembly 39 is connected across terminals 125 and 127 in a motor circuit including lines 131 and 133. This connection is ahead of the time-control switch 113. The main control switch 115 is connected in series with the motor in line 133. When switch 115 is closed, the motor circuit is energized and motor 40 drives the blower 41. The lines 131 and 133 include flexible leads to the motor to permit vertical movement thereof with the hollow standard 27.

The motor 40 also has a separate set of connections to terminals 125, 127 through the time-control switch 113. This is accomplished through an additional set of wires 114.

The air heater 103, selector switch 109 and circuit breaker 111 are connected in series across the motor circuit. As illustrated, a line 135 is connected at one end to line 133 at a terminal 137 and at its other end to a fixed contact member 139 of the switch 109. Terminal 137 is located between the main control switch 115 and the motor. Switch 109 comprises the fixed contact member 139, a rotary conductive hub 146 carrying three angularly spaced blades 141, 143 and 145, and a pair of fixed contacts 147 and 149 (note particularly Fig. 4). The hub is adapted to be rotated by a knob 151 (Fig. 1) to any one of three positions. In one position (Fig. 4) blade 141 engages contact member 139, blade 143 engages contact 147 and blade 145 engages contact 149. In a second position (Fig. 3), blade 141 engages contact member 139, and blade 145 engages contact 147, and electrical connection to contact 149 is broken. In a third position (not shown), all three blades are in circuit-breaking position.

Heating coils 105 and 107 have a common terminal at 152. The other terminals of coils 105 and 107 are connected by lines 153 and 155 to contacts 147 and 149, respectively. The terminals of circuit breaker 111 are connected by lines 157 and 159 to terminal 152 and line 131, respectively. Circuit breaker 111, as illustrated herein, comprises a pair of contacts, one of which is carried by a conductive thermostatic strip 161 and the other by a control button 162. When this strip overheats, the contacts separate and break the circuit for heater 103, also opening a latch 164. Otherwise this latch holds the contacts closed upon pushing in button 162.

The desiccant heaters 63 are connected in parallel in a desiccant heater circuit connected across terminals 125 and 127. This circuit includes lines 163 and 165 connected through a plug 166 to the heaters and including the time-control switch 113 in series with the heaters. The time-control switch may be of any suitable type for maintaining the desiccant heater circuit closed for the period required to reactivate the desiccant 61. It has a control knob 167 (Fig. 1) for closing the desiccant heater circuit and for setting the length of time for which the circuit is to remain closed. It also closes the circuit of motor 40 (through wires 114) for a short interval of time included at the end of the desiccant heating period. This assures that the desiccant spaces will be swept clear of moist or stale air. Preferably, the time-control switch is of the synchronous motor type, the motor being energized by A. C. in lines 163 and 165. Where the power 75

supply is D. C., a mechanical time-control switch may be used.

In using the hair drier, the drying hood 75 is adjusted by raising or lowering the standard 27 to a convenient height to accommodate the customer's head. The weight of the assembly comprising the hood, standard and the motor-blower assembly 39 is counterbalanced in any adjusted position by the spring counterbalances 51, and such adjustment may therefore be made with little manual effort. The main control switch 115 is closed to energize the blower motor 40. This also energizes air heater 103, assuming switch 109 to be either in the Fig. 3 or the Fig. 4 position. The time-control switch 113 is open at this time, so that desiccant heaters 63 are not energized, nor does it supply the motor current.

Upon energization of the blower motor 40, the blower 41 is driven and draws room air through louvers 37 into chamber 17, and through filter 65, the desiccant 61, and ports 25 into the compartment 19. The desiccant adsorbs almost all the moisture from the air as it flows therethrough so that the air drawn into compartment 19 has a very low relative humidity. This dry air is drawn through the blower inlet 43 and is delivered through the blower outlet 42, hose 45, and standard 27 to manifold 69. From manifold 69 it is distributed through nipples 79 to the air tubes 77 and flows out of the apertures 81 in small individual streams upon the customer's hair. Valve 83 may be opened, if desired, to obtain a single concentrated stream of air.

The dry air flowing through manifold 69 is warmed by heater 103 to a comfortable effective temperature prior to its emission from tubes 77 (or through port 83) so that it is pleasantly warm upon the customer's head. This warming of the air is most desirable, especially in the initial stage 40 of the hair-drying period, as the flow of dry air upon the wet hair has a substantial cooling effect. The temperature of the air may be manually controlled by means of selector switch 109 so that the flowing air has this comfortable effective 45 temperature. With switch 109 in the Fig. 4 position, both heating coils 105 and 107 are connected in parallel in the heater circuit so that both coils are energized for maximum heating effect. With switch 109 in the Fig. 3 position, only 50 coil 105 is energized, coil 107 being disconnected, for low-stage heating. If, for some reason, heater 103 should become too hot, the thermostatic circuit breaker 111 opens the circuit and deenergizes the heater 103 completely to prevent scorching or 55 burning of the customer's hair or head.

When the supply of desiccant has adsorbed its capacity of moisture, it may be reactivated by closing the time-control switch to energize desiccant heater 63. The timer will be set to maintain 60 these heaters energized for the length of time required to dry the desiccant, say four hours. This time will vary in accordance with local relative humidity conditions. When the drying period is near completion, the time-control switch 113 closes the motor circuit 114 for a short interval, say five minutes. This sweeps out any last vestige of moist or stale air. Finally the desiccant heater circuit and the motor circuit are both automatically opened. No attendance is required. It is contemplated that, in practice, the beauty shop operator will set the timer just before leaving the shop at the close of business to maintain the desiccant heaters energized for the desired several hours thereafter.

The air distributor 3, standard 27, dome 29,

motor-blower assembly 38, guides 53, counter-balances 57 and other connected parts may be lifted as a unit away from the base 5 to obtain access to the interior of the casing 11 or to parts normally within the casing. The dome 29 may be provided with a handle 161 for facilitating removal of this unit, and also for convenience in moving the hair drier from place to place.

From the above, it will be clear that dehydrated air at a comfortable effective temperature is discharged from the air distributor 3 upon the customer's hair for rapidly and comfortably drying it. The effective temperature (this term being used in its technical sense) of the air is dependent upon its dry and wet bulb temperatures and its rate of flow. The particular value of the effective temperature for comfort depends upon the degree of warmth or cold felt by the individual due to the flow of air upon her head. This invention provides for control of the effective temperature to a comfortable value while also providing for a supply of air which is practically dry for quick drying. This is a prime advantage over prior hair driers which merely blow moist room air at an uncomfortable effective temperature. With the present invention, the flow of practically dry air at a comfortable effective temperature dries an individual's hair in considerably less time than heretofore without any discomfort due to excessive heat.

Certain points of advantage of the invention should be definitely noted as follows: Heretofore heating was used only for the purpose of reducing the relative humidity of the air coming out of the hood 15. The air was not dried and this heating was the only means for conditioning the air to pick up moisture from the hair. Since it required a large increase in temperature to reduce the relative humidity to any substantial extent, there resulted the extreme discomfort above mentioned. Furthermore, the discomfort increased with the natural humidity of the air because such a condition required a higher temperature rise for a given reduction in relative humidity. Thus upon the humid days when the apparatus should desirably have operated cooler, it operated hotter; hence with more discomfort.

With the present invention, heating is not for the primary purpose of reducing the relative humidity since this is satisfactorily reduced by the desiccant. In fact, it is reduced to such an amount that the cooling effect due to fast evaporation upon fast drying is excessive and it is for that reason alone that the heater is used. Thus the only function of the heater is to prevent discomfort due to overcooling and for this purpose the temperature needs only be made equal to and no higher than that desired by the user. Not only is the user at a more comfortable temperature, but the waiting time for drying is reduced because the desiccant is much more efficient in drying the air than was the old method of reducing relative humidity merely by heating.

Thus it may be said that one factor of the invention is in the separation of the air drying and air heating functions, instead of simply having a heater perform both of these functions.

An additional advantage is that in a beauty shop all moisture abstracted from the drying hair of the customer is not, as heretofore, injected into the room but is trapped in the desiccant of the driers. With former apparatus this moisture gradually increased the humidity, particularly on humid days, to an uncomfortable point. By using the present invention the hu-

midity of a shop is not increased and may even be decreased because the desiccant in the driers tends ultimately to abstract moisture from the air of the shop.

The invention is to be distinguished also from the mere former use of old driers in air-conditioned shops. It is not feasible by means of an ordinary air-conditioning system to dry the air sufficiently to obtain the effect on the hair as obtained by the present invention. To gain this effect by such means would involve excessive cost and general over-all discomfort to occupants in a shop, due to excessively low humidity.

Also contributing to the comfort of the customer is the absence of immediate fan noise. In the present invention, the blower is in the base rather than in the drying hood. The suspension of the motor-blower assembly 38 from the lower end of the hollow standard 27 by means of the short length of flexible hose 45 is advantageous in that it eliminates vibration. Also, there are no moving parts in the drying hood to entangle hair and no possibility of harming the customer. Many beauty shop customers have a feeling of uneasiness toward prior hair driers due to the presence of the fan closely adjacent the head. There is no occasion for such a feeling with the present invention. Also, filtered air is used in each hair drying operation as a sanitary feature.

When the desiccant is heated to reactivate it the heaters bring the temperature up to over the boiling point of the water to turn it into steam. This action destroys all harmful germs and/or bacteria so that sterile air will be produced when the machine is put in use after dehydration.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

We claim:

1. A hair drier comprising a portable base including a vertical double-walled casing providing a chamber surrounding a compartment, said chamber being adapted to be filled with a porous, solid desiccant and having an air inlet adjacent one end and an outlet to said compartment adjacent its other end, a hollow standard mounted for vertical sliding movement in said base with its lower end extending into said compartment, a drying hood carried by the upper end of said standard above said base and in communication with said standard, and a blower in said compartment adapted to draw air through said chamber into said compartment and to deliver it through said standard to said hood.

2. A hair drier as set forth in claim 1, further including a heater for warming the air to a comfortable effective temperature prior to its emission from said hood.

3. A hair drier as set forth in claim 2, further including a heater in said chamber for heating said desiccant to dehydrate it.

4. A hair drier comprising a portable base including a vertical double-walled casing providing a chamber surrounding a compartment, said chamber being adapted to be filled with a porous, solid desiccant and having an air inlet adjacent one end and an outlet to said compartment adjacent its other end, a hollow standard mounted

for vertical sliding movement in said base with its lower end extending into said compartment, a drying hood carried by the upper end of said standard above said base and in communication with said standard, and a motor-blower assembly carried by the lower end of said standard within said compartment with the blower inlet opening into the compartment and the blower outlet in communication with said standard.

5. A hair drier comprising an air distributor for distributing a flow of air upon a head of hair, means providing a space for desiccant, a motor blower adapted to force air through said desiccant space and to the distributor, heater means for the desiccant space, a circuit for the heater means and the motor blower, a normally open interval timer switch in said circuit adapted to be closed to operate the heater means and the motor blower for predetermined intervals, the motor blower operating interval being less than and occurring at the end of the heater operating interval, means for operating the motor blower independently of the interval timer switch, and means for warming the air prior to its emission from the distributor during the latter operation of the motor blower.

6. A hair drier comprising an air distributor for distributing a flow of air upon a head of hair, means providing a space for desiccant, a motor blower adapted to force air through said desiccant space and to the distributor, a dry-air heater between the motor blower and the distributor, heater means for the desiccant space, a circuit for the heater means, motor blower and the dry-air heater, an energizing circuit for both heaters and the motor blower, a manual switch in said circuit for controlling energization of the motor blower and the dry-air heater, and a normally open interval timer switch in said circuit adapted upon a setting thereof independently of the manual switch to energize the desiccant heater means for a predetermined interval and to energize the motor blower for a predetermined interval at the end of the desiccating interval.

7. A hair drier comprising a base including a vertical double-walled casing providing a desiccant chamber surrounding a compartment, the chamber being open at its top for flow of air into the chamber and thence downward through the

desiccant in the chamber, and having an outlet at its lower end in communication with the compartment, a hollow standard mounted for vertical sliding movement in said base with its lower end extending into said compartment, a drying hood carried by the upper end of said standard above the base and in communication with said standard, and a blower associated with the base for causing a flow of air downward through the desiccant in the chamber to the compartment and thence through the standard to the hood.

8. A hair drier comprising a portable base including a vertical double-walled casing providing a desiccant chamber surrounding a compartment, the chamber being open at its top for flow of air into the chamber and thence downward through the desiccant in the chamber, and having an outlet at its lower end in communication with the compartment, a dome closing the upper end of the casing and having louvers for admitting air to the top of the chamber only, a hollow standard mounted for vertical sliding movement in said dome with its lower end extending into the compartment, a drying hood carried by the upper end of the standard above the base and in communication with the standard, and a blower associated with the base for causing a flow of air through the louvers and thence downward through the desiccant in the chamber to the compartment and thence through the standard to the hood.
